APPARATUS FOR TREATING CHEMICALS

Walter A. Carlson and Paul W. Salo, Minneapolis,
Minn., assignors to General Mills, Inc., a corporation of Delaware

Application August 3, 1940, Serial No. 351,020

6 Claims. (Cl. 23—267)

This invention relates to apparatus for treating chemicals and more particularly to apparatus for rapidly dissolving a chemical to be purified in a hot solvent, recovering the volatilized solvent and recrystallizing under conditions of controlled cooling.

An object of the invention is to provide a simple and efficient apparatus of this type for the purification of crystalline chemicals and for the recovery of their solvents.

Another object is the provision of a process for dissolving a chemical and for recovering the same in crystalline form under conditions which first cause rapid solution without the application of sufficient heat to injure delicate chemicals, such as those containing pro-vitamins like ergosterol, and then bringing about recrystallization of that chemical in the same apparatus under the most favorable conditions.

These and other objects as will hereinafter appear are accomplished in this invention which is fully described in the following specification and shown in the accompanying drawing in which

Figure 1 is a vertical section through the apparatus;

Fig. 2 is a partial end elevation of the motor for agitating;

Fig. 3 is a perspective view of a perforated container for holding the material to be treated;

Fig. 4 is a partial enlarged section on the line 4 of Fig. 3; and

Fig. 5 is a partial enlarged perspective view showing a clamp for holding the cloth on the frame of the container and agitator.

The embodiment illustrated comprises a kettle 10 preferably of stainless steel or other chemically inactive metal and having a liquid-tight jacket 11 surrounded by a heat insulating jacket 12 and provided with a heat insulated cover 13 which is secured thereto as by means of bolts 14.

A rod 15 preferably extends through the cover and is provided with a suitable packing gland 16. This rod carries a series of arms 17 terminating in a ring 18. A fine wire screen 19 is soldered to this ring so as to completely close the same and prevent the passage of the material to be treated past the screen. A cloth cover 20 depends from the ring 18 to which it is secured by means of a band 21, the ends of which are drawn together by any suitable form of clamp 22. The material A to be treated is placed within this cloth which serves as both a container and a filter since the material to be dissolved and recrystallized often contains impurities. These

are substantially all retained by the cloth and the screen.

The upper end of the rod connects through a suitable connecting rod 23 with a crank pin 24 on a plate 25 which is rotated at a suitable speed through a reduction gearing, not shown, by means of a motor 26.

Thus the container secured to the bottom of the rod 15 acts as an agitator when moved up and down by the connecting rod 25 and greatly increases the rate of solution of the chemical A in the solvent B in the kettle. This solvent is purposely kept well below the top of the kettle so as to leave a clear space 30 into which the filter member 20 can be raised as shown in dotted lines. A suitable chain and hook 31 are provided for fastening the rod in the elevated position so as to permit the filter 20 to be raised to the dotted position in which the residual solvent may drain therefrom.

A pipe 33 supplied with a valve 34 connects with the bottom of the jacket 11 and serves as a drain. The jacket also connects through a horizontal pipe 35 with a vertical pipe 36 which in turn connects through a valve 37, a cylinder 38 and a pipe 39 with the top of the jacket. An expansion tank 40 connects through a pipe 41 with the top of the jacket and has an overflow pipe 42. A pipe 43 having a valve 44 leads down from the pipe 35 and connects with the water supply. A coil 45 is located in the cylinder 38 and has pipes 46, 47 by means of which hot or cold liquids or steam may be circulated through the coil for heating or cooling the water in the cylinder 38. A pipe 48 controlled by a valve 49 is connected to a suitable source of steam and is provided with an injector 50 for heating the jacket as well as insuring positive circulation through the cylinder 38 and the pipe 39 during the heating cycle.

The passage at the bottom of the kettle is covered by a screen 55 and leads to a three-way valve 56, one side of the valve connecting through a pipe 57 with a receiver 58 and the bottom to a drain. The receiver is provided with a vent 58a. For convenience, a thermometer 59 is provided for reading the temperature of the jacket 11 and a thermometer 60 shows the temperature of the liquid B.

A pipe 65 leads from the space 30 above the liquid in the kettle to a condenser 66 and thence through a sight box 67 to a receiver 68 which is provided with a vent, 68a. A coil 69 in the cylinder 66 is supplied with cold water through a

pipe 10, the water being carried to a drain through a pipe 11.

Thus it will be seen that the solvent B in the kettle vaporizes and passes over through the cooling coil 69 where it is condensed and passes into the receiver 68 as recovered solvent C. This receiver is drained by means of a pipe 15 which connects through a valve 16 with a hand pump 17 the delivery side of which connects through a pipe 18 with a pipe 65. The intake of the pump 17 also connects through a valve 19 and a pipe 80 with the bottom of the receiver 68. The receiver 68 may also be drained by means of a valve 81, and the receiver 68 may be drained by a valve 82.

Thus the recovered and purified solvent C in the receiver 68 may be returned to the kettle by opening the valve 18 while the valve 19 remains closed. On the other hand, the liquid D in the receiver 68 is the unvaporized residue which has been drained from the kettle and this may be returned to the kettle if desired by opening the valve 19 while the valve 18 remains closed by the operation of the pump 17.

It will be apparent that by means of the kettle and its associated parts, the operator has a piece of apparatus by which he can perform a multiplicity of operations and control the speed of those operations to a very high degree.

Thus he takes a material like ergosterol which contains impurities and places them within the filter bag at the bottom of the agitator. He then tightly clamps the cover on the kettle and heats the water within the jacket 11 by means of steam from the pipe 48 and proceeds to agitate the filter assembly 20 in the solvent B. During this operation some of the solvent may boil off in which case it is cooled by the coil 69 and falls into the receiver 68. This operation then continues until the ergosterol or other chemical is sufficiently dissolved in the solvent after which the cloth bag is raised to the dotted line position of Figure 1 and permitted to drain into the kettle. This operation constitutes an instantaneous hot filtration, and eliminates a jacketed pump and pipes normally required, as well as a second tank needed as a receiver after filtration.

Cooling the liquid B will now cause the dissolved ergosterol to recrystallize on the walls of the kettle. The rapidity with which this occurs will depend very largely on the rapidity of cooling this liquid. If all of the valves 34, 37 and 44 are closed, the water in the jacket will cool but slowly, due to the efficiency of the heat insulation 12. If, however, it is desired that the rate of cooling be accelerated, the operator will open the valve 37 and a thermosyphon action will take place which will greatly increase the rate of cooling due to the fact that the cylinder 38 is not heat insulated. Should he wish to increase the rate still further, cooling water is allowed to circulate through coil 45. This accelerates the thermosyphon and yet gives good control of the cooling rate. By this method, there are no large local differences in temperature in the jacket. A greater increased cooling rate may be obtained by admitting cold water to valve 44, the hot water overflowing through the expansion tank. When cooling is done by this method, there is an abrupt change in temperature as the level of the cooling water gradually rises from the intake valve and finally reaches the expansion tank.

Thus it will be seen that a very efficient and

self-contained apparatus is provided for the recovery of certain chemicals in purified crystalline form; the operator is enabled to control the rate of solution and recrystallization to a very high degree in addition to carrying out such usual operations as recovery of solvent.

After the mother liquor has been drawn off through the valve 56, the crystals deposited on the walls of the kettle may be washed with any suitable liquid such as a small amount of the purified solvent C in receiver 68 which may be forced into the kettle by the pump 17 and then drained off by the valve 56. These crystals may then be removed from the kettle and spread out to dry.

This type of apparatus has been found very useful for purifying such materials as ergosterol as described in the example. It is also similarly useful for extraction of drugs and other chemicals from a mass consisting of unimportant insoluble or partly soluble material. At times when the apparatus is used for such purpose, it is naturally convenient to carry out a simultaneous crystallization of the extracted material. If the extraction has been carried out with hot solvent, it will often be possible to crystallize merely upon cooling the solvent. At other times, it will be found necessary to distill off part of the solvent after extraction has been completed and then crystallize the product from the resulting concentrated solution. It is also obvious that solvent recovery may be carried out in the apparatus as a separate operation to provide fresh solvent for future extractions. This and other variations of the use of the equipment would be obvious to the operator.

Depending upon the size and construction of the equipment, some of the details of construction can be varied considerably; for example: instead of having a removable cover, it is possible to have a completely enclosed tank to which access is allowed by means of a manhole; after each operation, the product can be removed and new material introduced through such an opening.

Similarly the water jacket may be replaced by a steam jacket or by means of hot air as desired. However, in such a case one loses the advantages of the thermosyphon method of controlling the rate of cooling.

We claim as our invention:

1. Apparatus of the class described comprising a kettle having a jacket for holding a heat exchange medium, a closure for the kettle, a porous container constructed to hold a substance to be treated within the kettle, supporting means for the container extending through the closure, driving means connected to the supporting means for reciprocating the container through a predetermined path within the kettle, and means associated with the supporting means for lifting and maintaining the container above said path.

2. Apparatus of the class described comprising a kettle having a jacket for holding a heat exchange medium, a closure for the kettle, a porous container constructed to hold a substance to be treated within the kettle, supporting means for the container extending through the closure, driving means connected to the supporting means for reciprocating the container through a predetermined path within the kettle, means associated with the supporting means for lifting and maintaining the container above said path, piping connected to the top and bottom portions of the kettle jacket, and said piping having means for introducing, withdrawing and circulating the

heat exchange medium within the piping and jacket.

3. Apparatus of the class described comprising a kettle having a jacket for holding a heat exchange medium, a closure for the kettle, a porous container constructed to hold a substance to be treated within the kettle, supporting means for the container extending through the closure, driving means connected to the supporting means for reciprocating the container through a predetermined path within the kettle, means associated with the supporting means for lifting and maintaining the container above said path, piping connecting the top and bottom portions of the kettle jacket, and valve means in said piping for controlling the flow of the heat exchange medium therethrough.

4. Apparatus of the class described comprising a kettle having a jacket for holding a heat exchange medium, a closure for the kettle, a porous container constructed to hold a substance to be treated within the kettle, supporting means for the container extending through the closure, driving means connected to the supporting means for reciprocating the container through a predetermined path within the kettle, means associated with the supporting means for lifting and maintaining the container above said path, piping connecting the top and bottom portions of the kettle jacket, said piping having means for circulating and controlling the flow of the heat exchange medium within the jacket, and means associated with the piping for varying the temperature of the heat exchange medium therein.

5. Apparatus of the class described comprising a kettle having a jacket for holding a heat exchange medium, a closure for the kettle, a porous container constructed to hold a substance to be treated within the kettle, supporting means for the container extending through the closure, driving means connected to the supporting means

for reciprocating the container through a predetermined path within the kettle, means associated with the supporting means for lifting and maintaining the container above said path, piping connected to an upper portion of the kettle for withdrawing vapors therefrom, condensing and collecting means connected to said piping, means connected to a bottom portion of the kettle for withdrawing and collecting liquid therefrom, and a pump having piping connected to each of said collecting means and to the kettle for returning liquid to the kettle.

6. Apparatus of the class described comprising a kettle having a jacket for holding a heat exchange medium, a closure for the kettle, a porous container constructed to hold a substance to be treated within the kettle, supporting means for the container extending through the closure, driving means connected to the supporting means for reciprocating the container through a predetermined path within the kettle, means associated with the supporting means for lifting and maintaining the container above said path, piping connected to an upper portion of the kettle for withdrawing vapors therefrom, condensing and collecting means connected to said piping, means connected to a bottom portion of the kettle for withdrawing and collecting liquid therefrom, a pump having piping connected to each of said collecting means and to the kettle for returning liquid to the kettle, other piping connecting the top and bottom portions of the kettle jacket, said other piping having means for circulating and controlling the flow of heat exchange medium within the jacket, and means associated with said other piping for varying the temperature of the heat exchange medium therein.
